(57) **CLAIM**

The ornamental design for an information display for vehicle, as shown and described.

DESCRIPTION

FIG. 1 is a perspective view of the front, right, and top side of an information display for vehicle showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference view of our information display for vehicle thereof showing the example of the display part being activated;

FIG. 9 is a perspective view of the front, right, and top side of an information display for vehicle showing the second embodiment of our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a reference view of our information display for vehicle thereof showing the example of the display part being activated.

The broken lines showing our information display for vehicle embodied in a dashboard of a vehicle is for the purpose of illustrating environmental structure and forms no part of the claimed design.

1 Claim, 16 Drawing Sheets
